UNITED STATES PATENT OFFICE.

WILLIAM D. TYLER, OF DENVER, COLORADO.

BELT-TIGHTENER.

SPECIFICATION forming part of Letters Patent No. 472,967, dated April 12, 1892.

Application filed July 24, 1891. Serial No. 400,648. (No model.)

To all whom it may concern:

Be it known that I, WILLIAM D. TYLER, a citizen of the United States of America, residing at Denver, in the county of Arapahoe and State of Colorado, have invented certain new and useful Improvements in Belt-Tighteners; and I do declare the following to be a full, clear, and exact description of the invention, such as will enable others skilled in the art to which it appertains to make and use the same, reference being had to the accompanying drawings, and to the figures of reference marked thereon, which form a part of this specification.

15 My invention relates to improvements in belt-tighteners for use where machinery located on one floor of a building is propelled by a power located on a floor below. For instance, in electric-power plants of considerable 20 magnitude many of the dynamos are often located above the first floor of the building, while the engine propelling them is placed on the first or lower floor. The power is then transmitted from pulleys on a main shaft below, 25 through the medium of suitable belts, to the pulleys on the armature-shafts on the dynamos. In tightening these belts, therefore, the dynamo, which is mounted upon a movable sliding frame, has been moved in a horizontal 30 plane to one side of a perpendicular line connecting the shafts upon which the pulleys are located. It will be observed that by this lateral movement in a horizontal plane the distance between the centers of the shafts is 35 increased by the difference between the length of the perpendicular and the length of the hypotenuse of a right-angled triangle, of which a line connecting the centers of the two shafts before movement would form the perpendicular, the line in which the center of the 40 moving shaft has traveled the base, and a line connecting the centers of the shaft after movement the hypotenuse. A considerable lateral movement has thus been found necessary 45 in order to give the belts the desired tension, and the greater this lateral movement the greater the space which must be allowed each machine in order to give room for adjustment. Hence for the purpose of economizing space it has been found desirable to 50 tighten these belts without relying entirely

upon the lateral movement of the overhead machines.

The object, therefore, of my invention is to provide a means for tightening belts leading 55 to machines located above the propelling-power, which means shall reduce to a minimum the space necessary for lateral movement and at the same time subserve the requirements of efficiency, ease of adjustment, 60 durability in use, and economy in cost. This object I accomplish by the use of the mechanism illustrated in the accompanying drawings, in which—

Figure 1 is a side elevation of the device, 65 showing the overhead machines in place. Fig. 2 is a plan view with the machine removed. Fig. 3 is a fragmentary view illustrating a means of adjustment; Fig. 4, an elevation of my improved belt-tightening means. 70

In the views, similar reference characters indicating corresponding parts or elements of the mechanism, let the numeral 5 designate a dynamo, which may be considered typical of any suitable overhead machine provided with 75 a shaft 6, upon which is rigidly mounted a pulley 7, connected through the medium of a belt 8 with another pulley 9, mounted upon a shaft 10, suitably journaled upon a floor below and driven by suitable power. The dynamo 5 is mounted upon a movable support or frame consisting of two beams 12, connected by suitable cross-bars 13. The upper surfaces of beams 12 lie in a horizontal plane, so as to support the machine in an upright position, while the lower surfaces of these beams form inclined planes engaging the oppositely-inclined faces of other beams 14, resting upon and rigidly secured to the floor 15. These engaging faces of the stationary and movable 85 frame are oppositely shouldered, as shown at 20, in order to maintain the frames at all times in the proper relative position.

The movable frame may be adjusted in any suitable manner, as by the screw-bolt, lever-arm, ratchet, and pawl shown in the drawings. The screw-bolt 25 consists of a plain portion passing through a suitable aperture formed in a cross-beam 13 of the movable frame and adapted to rotate freely therein, 95 and a threaded portion engaging a correspondingly-threaded nut 26, made fast to the

stationary cross-beams 27 of the stationary frame 14. The outer extremity of the screw-bolt is provided with the ratchet-head 28, rigidly secured thereto, and the movable lever-arm 29, provided with the pawl 30, pivoted thereon and adapted to engage the ratchet-disk. The screw-bolt occupies a position parallel with the inclined engaging faces of the two frames. This bolt may occupy a position parallel with the horizontal faces of the frames; but in this case the nut 26 must have a vertical movement and be provided with guides. It will be observed that by the use of the lever-arm, pawl, and ratchet the screw-bolt may be rotated. Now as the nut is stationary the bolt moves therethrough and carries the movable frame toward the right or up the inclined face of the stationary frame. In this case the dynamo-shaft, instead of moving in a horizontal plane, moves upward in an inclined plane, its path lying parallel with the inclined face of the stationary frame, and the advantage gained over a simple lateral movement will be readily observed. This advantage will of course depend upon the inclination of the engaging faces of the frames, and in any event will be the length of the perpendicular of the right-angled triangle formed by drawing a direct line from the original location of the center of the dynamo-shaft to the center of this shaft in the changed position and then drawing a perpendicular line from the last-named point to intersect a horizontal line drawn from the first-named point. In this case the horizontal line will be the base, while the line in which the center of the shaft moves will form the hypotenuse of the triangle. Hence the lateral movement of the machines may be correspondingly diminished and the same tightening result attained.

It will be observed that both the inclined

frames may be movable and simultaneously shifted in opposite directions by the use of a double-screw-actuating mechanism, one screw-bolt and its attachments being connected with each frame. In this case the belt may be tightened in one-half the time necessary where only a single screw is employed and but one frame moved. 45

Having thus described my invention, what I 50 claim is—

1. In a belt-tightener for machines located above the propelling-shaft, the combination of two frames having oppositely-disposed inclined engaging faces, one of said frames being movable, an actuating screw-shaft, and a stationary support connected with the movable frame by the actuating-shaft, said shaft being swiveled in one of the connected parts and engaging a threaded socket in the other parts, and suitable means for rotating the actuating-screw, whereby the movable frame is shifted, substantially as described. 55

2. In a belt-tightener, the combination of two frames having oppositely-disposed inclined engaging faces, the upper frame being movable and the lower stationary, and an actuating-screw-shaft occupying a position parallel with the inclined engaging faces of the frames, said shaft being swiveled in the movable 70 frame and engaging a threaded socket in the stationary frame, the outer extremity of the shaft being provided with a rigid ratchet-head and a movable lever-arm and engaging pawl, substantially as described. 75

In testimony whereof I affix my signature in presence of two witnesses.

WILLIAM D. TYLER.
